UNITED STATES PATENT OFFICE.

HENRY W. FISHEL, OF NEW YORK, N. Y., ASSIGNOR TO HIMSELF AND THEODORE H. FISHEL,
COPARTNERS TRADING AS FISHEL, NESSLER & CO., OF NEW YORK, N. Y.

DESIGN FOR A BROOCH-PIN.

No. 39,278.

Specification for Design.

Patented April 28, 1908.

Application filed March 27, 1908. Serial No. 423,792. Term of patent 14 years.

To all whom it may concern:

Be it known that I, HENRY W. FISHEL, a citizen of the United States, residing at the borough of Manhattan, city of New York, in the county of New York and State of New York, have invented a certain new, original, and ornamental Design for Brooch-Pins, of which the following is a specification, reference being had therein to the accompanying drawings, forming part thereof.

Figure 1 is a face view of a brooch-pin showing my new design. Fig. 2 is an end view of the same.

I claim:

The ornamental design for a brooch-pin as shown.

HENRY W. FISHEL.
